TRANSDUCER

Emile C. Guedon, Audubon, N. J., assignor to
Radio Corporation of America, a corporation
of Delaware

Application July 31, 1935, Serial No. 34,016

10 Claims. (Cl. 179—100.41)

The present invention relates to transducers or translating devices for converting or translating electrical signal currents into corresponding mechanical movement of an armature member 5 and for converting or translating mechanical movement of said armature member into corresponding electrical currents.

More particularly, the invention relates to transducers of the electromagnetic pickup type employed in phonograph recording and reproducing systems and comprising a vibratory armature adapted to carry a stylus or needle, an electric pickup coil surrounding the armature and a permanent magnet associated with the 15 armature and the coil to provide exciting flux.

The invention has for its primary object to provide an improved and simplified construction in a transducer device of the character referred to having operating elements which may be more 20 rapidly and easily assembled and adjusted in predetermined relation to each other and which may withstand more severe handling in shipment and in servicing than has heretofore been possible in like devices.

It has been the practice heretofore in transducers of the electric pickup type to provide a pair of pole pieces for the permanent magnet having an air gap maintained constant by a non-magnetic bridge piece connecting the pole pieces. 25 The magnet itself is usually removable from the pole pieces, being held thereon merely by a spring tension or by magnetic attraction alone. Because of this arrangement the magnetic circuit was often momentarily broken when the magnet was moved by vibration or by accident in servicing the device, with the result that the magnetic field thereafter was greatly reduced in strength 30 and required recharging of the magnet before efficient operation could be obtained.

It is, therefore, a further object of the present invention to provide an improved magnet and pole piece construction in a transducer device of the electro-magnetic pickup type, where-in the air gap is maintained at a permanent 35 predetermined width by the magnet itself acting as a yoke, permanently welded to the pole piece.

It is also a still further object of the invention to provide an arrangement of parts in a transducer device of the electro-magnetic pickup type 40 which renders such a device compact in construction and highly efficient electrically in producing relatively high output potentials in response to normal vibratory movement of the armature.

The invention will, however, be better understood from the following description when con-

sidered in connection with the accompanying drawing and its scope will be pointed out in the appended claims.

In the drawing, Fig. 1 is a front view on a greatly enlarged scale of an electro-magnetic 5 pickup device or transducer embodying the invention, with a cover removed to expose the interior mechanism;

Fig. 2 is a cross sectional view of the device shown in Fig. 1 and on the same scale, taken on 10 line 2—2 and with the cover in place;

Fig. 3 is a bottom view of the device shown in Fig. 1 also on the same scale;

Figs. 4 and 5 are front views, substantially full size and on a reduced scale from Figs. 1, 2 and 15 3, showing the magnet and pole piece assembly before and after completion; and

Fig. 6 is a detail view, partly in cross section and on a greatly enlarged scale over that of 20 Figs. 1, 2 and 3, of the armature assembly of the device of Figs. 1, 2 and 3.

Referring to the drawing, 7 is a molded composition base of insulated material adapted to receive front and rear cover plates 8 and 9 to form therewith a housing or casing for the transducer operating mechanism. The base plate is provided with a rear extension or shank 10 for connection with a suitable tone arm (not shown), and embedded therein are the usual electrical 25 terminal means 11 for the device.

The base is provided with two spaced depending leg portions 12 and each is provided with an elongated slot or opening as indicated at 13 for receiving a clamping screw indicated at 14 for the interior mechanism. The clamping bolts also 30 engage a portion of a rear cover 15 for the mechanism to hold said cover in place.

On the interior face of the base, a unitary magnet structure is provided, comprising a U-shaped permanent magnet 16 and a pole piece 17 as 35 shown more clearly in Fig. 4. The pole piece 17 is provided with welding points 18 for engaging the poles of the permanent magnet 16 and is thereby spot welded as indicated in Fig. 5 to provide a good magnetic joint at 19, that is, a tight 45 joint having low reluctance.

The construction shown further includes in the pole piece, two rectangular end portions indicated in Fig. 5 at 17a and 17b providing a flat surface at 22 to permit the magnet unit to be 50 seated on a magnetized device (not shown) and properly charged. The pole piece ends 17a and 17b are substantially of the same cross sectional area as the magnet 16 and between the ends the pole piece is recessed as indicated at 23, Figs. 55

4 and 5 to provide a thin bridge portion 24 through which the air gap slot 20 is made by cutting or milling after welding the ends to the magnet. 5

It will be seen that a unitary pole piece and magnet structure is thus provided in which the pole piece is welded to the magnet so as to insure a good magnetic circuit at all times even when the pickup device is being serviced in the field. 10

The magnet acts as a bridge or yoke to maintain a constant air gap between the severed portions of the pole piece without utilizing a special connecting link or bridge piece as has been necessary heretofore. The thin wall bridge portion of 15 the pole piece is furthermore reduced in cross section at the center on a taper forming the end sections toward the center whereby the resulting pole tips 25, Fig. 5 are tapered. The air gap is, therefore, substantially equal in length to the width of the armature tail or upper end herein- 20 after described.

The unitary pole piece and magnet structure is provided with two tapped holes 26 to receive the clamping screws 14 through the slots 13 and permits the magnet structure to be adjusted on the base 7 before being finally clamped in position. 25

A pickup coil or winding 27 is mounted on a flat strip of insulating material 28, which is seated against the bottom or lower ends of the pole piece. The pole piece ends are also tapped to receive armature clamping screws 29, which serve to draw a clamping plate 30 against the mounting strip 28 as shown to return the latter in a seated position against the ends of the pole piece 35 and to clamp the ends 31-32 of the armature pivot shaft. The plate or armature clamp 30 is of non-magnetic material, preferably of zinc alloy.

The armature pivot shaft is integral with the armature 33 which extends through the coil 27 and the space or large air gap 23, into the main or narrow air gap 20. The armature pivot shaft is surrounded by a spacer cushion preferably of rubber in the form of sleeves 34 whereby the armature is resiliently mounted when the clamping screws 29 are tightened as shown in Fig. 1. The armature pivot shaft portion 32 is tapped to receive a needle clamping screw 35 and extends frontly to receive the curled end of a centering spring 36 which is soldered or otherwise suitably secured thereto as shown in Figs. 1, 2 and 6 particularly. The centering spring is bent at an angle to lie across one frontal face of the pole piece to be clamped by a clamping piece 37 drawn inwardly to grip it by a bolt 38 which is threaded into one of the tapped openings 26 in the pole piece.

It will be noted that the armature clamp 30 and the coil mounting strip 28 are slotted about 60 the clamping screw 29 to permit adjustment of the two members with the coil 27 and the armature 33 to center the armature tail or free end later in the air gap 20 as shown, particularly in Fig. 1, before tightening the clamping member 65 37 by means of the bolt 38.

The opposite or rear end of the armature pivot shaft is extended to receive a block or strip of inert damping material, such as Viscoloid, a Du Pont product, indicated at 39, one end of the strip 70 being pressed on to the armature shaft as shown more particularly in Figs. 2 and 6, with the opposite end extending upwardly to a position wherein it is clamped against the base member 7. A clamping screw 40 extending through the 75 base into a combined bracket and clamping mem-

ber 41 serves to clamp the upper end of the damper block, as indicated particularly in Fig. 2. A cover screw 43 engaging the bracket 41 through an opening in the outer cover member, as shown in Fig. 2, serves to hold the cover in position.

In order that the damping block 39 may not be under tension or compression, the clamping screws 14 are released slightly when the screw 40 is inserted through the block. The screws 14 are then tightened to hold the assembly on the base. 10 The damping block is secured to the armature shaft by friction and, to provide a tight joint, the armature shaft end is slightly heated to cause the material to melt and flow about the shaft when the armature assembly is completed as shown in 15 Fig. 6. It will be seen that with this construction the armature spring and damping block together with the armature spacer cushions may be assembled as a unit.

The pickup coil or winding 27 is provided with 20 output leads 44 which are connected to the terminals 11, as shown. The armature is provided with an axially extending recess for receiving a stylus or needle 45 of any suitable type and the needle is retained therein by the needle 25 screw 35 as indicated in Fig. 2.

A second unit of the construction comprises the coil 27 and mounting strip 28 therefor which may be assembled with the magnet and pole piece structure and as a completed unit is 30 entirely removable from the base 7 without disturbing the relation between the magnet and its pole piece and without disturbing the air gap and the flux existing in the magnetic circuit. It will be seen that the magnetic circuit may not be 35 broken by accidental separation of the parts and that the air gap is permanently fixed to a pre-determined width.

It will further be seen that with the construction shown, the pickup coil or winding lies within 40 a relatively wide air gap between magnetic poles and the armature extends through the coil into a relatively narrow thin air gap forming the only low reluctance path for the flux since the armature clamping plate is of non-magnetic material. The pickup winding, therefore, lies within the normal flux path of the magnet and only the tip 45 of the armature lies in the main or narrow air gap. It has been found that this arrangement provides high fidelity in the translation of signals from and to a phonograph record in connection with an audio frequency signal circuit.

It will further be seen that an advantage in the construction shown resides in the unitary magnet and pole piece construction wherein the magnet 55 is U-shaped providing spaced poles and a pole piece having end portions welded to the poles of the magnet to provide a low reluctance flux path through the joint.

A further advantage in this construction lies 60 in the fact that the magnet itself forms a yoke for the pole pieces or pole piece to maintain a fixed air gap without additional bridge elements. The air gap is formed by cutting or slotting the pole piece through the thin central web after 65 welding to the magnet. In this manner the pole piece is prevented from becoming separated from the magnet to break the magnetic circuit, and the air gap is maintained permanently at a desired width.

The entire construction of the device is arranged to facilitate assembly inspection and adjustment, and to prevent impairment of operation in the field.

I claim as my invention:

1. A magnet assembly for an electro-magnetic transducer device comprising a magnet, a pole piece of magnetic material united therewith by fusion of metal providing an air gap maintained permanent wholly by said magnet as a yoke, said pole piece having a thin bridge portion provided with a slot to form said air gap, said bridge portion providing the only magnetic conducting path external to the magnet between the ends of said pole piece, an electrical winding within the pole piece adjacent to said bridge portion, and an armature member extending through the winding and into said air gap.
2. In an electro-magnetic pickup device, a unitary pole piece and magnet structure comprising a U-shaped magnet, and a pole piece member of magnetic material extending between and welded to the poles of said magnet, said member having a thin web between the poles and an air gap therein maintained fixed in width wholly by said magnet as yoke, and providing the only magnetic conducting path external to the magnet between the ends of the pole piece member.
3. In an electro-magnetic pickup device, the combination with a U-shaped magnet, of a unitary pole piece of magnetic material permanently united therewith at the magnet pole faces, said pole piece providing a portion adjacent each pole of the magnet of substantially the same cross-sectional area as the magnet and a thin unitary bridge portion therebetween of lesser cross-sectional area, said bridge portion constituting the only magnetic conducting element external to the magnet between the ends of said pole piece and having a slot providing an air gap between said ends and said magnet thereby providing a yoke to hold said pole piece permanently with said air gap fixed.
4. In an electro-magnetic pickup device, the combination with a magnet having poles in spaced relation to each other, of a pole piece permanently united with said poles and extending therebetween, said pole piece providing end portions of relatively large cross-sectional area, one adjacent to and contacting each of said poles, and a thin unitary bridge portion of lesser cross-sectional area therebetween having a slot providing an air gap between the magnet poles, said magnet thereby providing a yoke to hold said pole piece permanently with said air gap fixed, and said bridge portion providing the only magnetic conducting member external to the magnet and between the poles thereof.
5. An electro-mechanical translating device comprising a magnet having poles aligned to provide a gap between them, a pole piece member of magnetic material bridging said gap and united at its end portions with the magnet poles by fusion therewith, and said member having between its end portions a thin bridge portion of relatively small cross-sectional area providing the only magnetic circuit element external to the magnet between said end and having an air gap maintained constant in width by said magnet as a yoke.
6. An electromagnetic pickup device comprising a U-shaped magnet, a pole piece member of magnetic material having ends welded to the magnet poles and having a thin intermediate web slotted to provide a fixed air gap maintained permanent wholly by said magnet as a yoke and providing the only magnetic conducting path external to the magnet between the magnet poles, said magnet and pole piece thereby providing a unitary mag-
- net and pole piece structure, a flat plate of non-magnetic material engaging the pole piece ends in spaced parallel relation to said central web, a coil mounted on and secured to said plate between said plate and said central web, a vibratory armature extending through the coil and into the air gap, means providing a pivot shaft for the armature extending transversely of said coil support, a clamping plate of non-magnetic material for engaging the armature shaft, and means for adjustably securing said clamping and mounting plates to said pole piece member.
7. An electromagnetic pickup device comprising a U-shaped magnet, a pole piece member having ends welded to the magnet poles and having a thin central web slotted to provide a fixed air gap, said magnet and pole piece thereby providing a unitary magnet and pole piece structure, a flat plate of non-magnetic material engaging the pole piece ends in spaced parallel relation to said central web, a coil mounted on and secured to said plate between said plate and said central web, a vibratory armature extending through the coil and into the air gap, means providing a pivot shaft for the armature extending transversely of said coil support, a centering spring for the armature secured at one end to one end of said pivot shaft, means for adjustably clamping the opposite end of the armature centering spring to one end of the pole piece, a block of vibration damping material connected with the opposite end of said pivot shaft, a base for said pickup device, means for clamping said block of damping material to said base in spaced relation to its connection with the pivot shaft, and means for adjustably securing said unitary magnet and pole piece structure to said base member.
8. An electromagnetic pickup device comprising a U-shaped magnet, a pole piece member having ends welded to the magnet poles and having a thin central web slotted to provide a fixed air gap, said magnet and pole piece thereby providing a unitary magnet and pole piece structure, a flat plate of non-magnetic material engaging the pole piece ends in spaced parallel relation to said central web, a coil mounted on and secured to said plate between said plate and said central web, a vibratory armature extending through the coil and into the air gap, means providing a pivot shaft for the armature extending transversely of said coil support, means providing a resilient bearing for the pivot shaft on opposite sides of and adjacent to the armature, the ends of the shaft projecting axially from said bearing means, a centering spring for the armature secured to one projecting end of said shaft, and a block of vibration damping material secured to the opposite projecting end of said shaft.
9. A transducer of the electromagnetic pickup type comprising in combination a base member of insulating material, a magnet and pole piece structure comprising a U-shaped permanent magnet and a rectangular pole piece bridge across the ends of said magnet and welded thereto to provide a low reluctance magnetic circuit, said pole piece being recessed intermediate between its ends to receive a pickup winding and to provide a thin bridge between the ends of the magnet, and said bridge portion having a transverse slot and being tapered from the ends in the direction of said slot to provide an air gap of predetermined width and length, an armature having one end positioned in said air gap and having an armature pivot shaft integral therewith extending transversely on opposite sides thereof, means providing

- a resilient pivot bearing for said armature shaft, an armature centering spring secured to one end of said pivot shaft, means for clamping said spring to said pole piece, a block of vibration damping material mounted on the opposite end of said armature, means for clamping said block of damping material to the base member, and means for adjustably clamping said magnet and pole piece structure to said base member.
10. In an electromagnetic transducer device, a unitary magnet and pole piece structure having an air gap maintained permanent in width by the

magnet element thereof as a yoke and having a thin severed central web providing pole tips, said web forming the only low reluctance flux path between the magnet poles, an electrical pickup winding lying within the normal flux path of said magnet and pole piece structure, and an armature extending through the coil and into the air gap, said armature having a pivot shaft, an armature centering spring connected with one end of said shaft and a block of vibration damping material connected with the opposite end of said shaft. 10

EMILE C. GUEDON.
